NEGATIVE HOLDER

Morris Israel Shwartz, Providence, R. I.

Application October 7, 1933, Serial No. 692,626

2 Claims. (Cl. 88—24)

My invention relates to a negative holder designed for use in photographic printers, enlargers and the like, although it will be understood that the holder is susceptible for use with a variety 5 of devices wherein a photographic negative is to be held for illumination or the like.

The principal object of my invention lies in the provision of a holder provided with a hinged negative engaging member having resilient 10 operating means therefor whereby the same is frictionally held under tension in its closed position but which may be readily and easily lifted to permit the insertion and removal of the negative.

15 Another object lies in the provision of a guiding means for the hinged holder portion in its closing positions.

Still another object lies in the provision of novel flanged arrangement on the hinged holder portion 20 for engaging the negative to hold it flat.

Other objects and advantages will be apparent as the description proceeds, reference now being had to the figures of the accompanying drawing forming a part of this application and wherein 25 like reference numerals indicate like parts.

In the drawing:

Figure 1 is a perspective view of my improved holder illustrating the hinged portion in raised or open position.

30 Figure 2 is a top plan view of the holder in closed position.

Figure 3 is a detail sectional view of the holder taken on the line 3—3 of Figure 2.

The reference character 1 indicates a flat plate 35 or base to which is hinged as at 2 the movable holder member 3. This hinged member 3 is provided with a finger piece 4 whereby the same may be lifted from engagement with the plate 5.

The plate 1 is provided with an opening 5 40 which may be of any desired size depending upon the size of negative to be used in the holder. The hinged portion 3 is also provided centrally with an opening 6 adapted to register with the opening 5 when the hinged portion is folded down flat 45 against the plate 1. The edges of the opening 6 are provided with downwardly turned film engaging flanges 7 which pass through the opening 5 in the plate 1 for direct contact engagement with the negative 8 positioned beneath the hinged 50 portion 3 on the plate 1 as shown clearly in Figure 3.

One edge of the opening 5 is provided with a notch 9 whereby the edge of a negative can be readily grasped by the fingers of the operator.

55 Provided upon the plate 1 are a pair of guide pins 10 adapted to pass through similarly disposed openings 11 in the hinged member 3 whereby such hinged member is guided to its properly closed position. This is an important feature 60 due to the fact that the member 3 is loosely hinged

at 2 in order to compensate for the thickness of the negative placed between member 3 and the plate 1. This loose hinge arrangement is provided by the enlarged hinge openings 12.

Adjacent each end of the opening 5 the plate 1 is provided on its upper side with spring arms 13 carrying at their free ends rounded tension fingers 14 normally in position to engage the corresponding edges of the hinged holder 3 when it is swung down to closed position as shown in Figure 2. These fingers 14 yield with the springs 13 to permit the hinged member to assume its closed position with respect to the plate 1 and the tension of the springs serves to frictionally hold the hinged member in closed position but permits the ready lifting thereof when it is desired to remove the negative therefrom.

In use a support 15 is usually provided with an opening 16 therethrough for passage of light upward. Provided on this support 15 and covering the opening 16 is a glass or transparent member 17 upon which the holder plate 1 rests and which may be suitably secured in any desired manner. It will be obvious, of course, that the openings 5 and 6 of the negative holder will register with the opening 16 through which the light passes.

Of course, changes may be made in details of construction and arrangement of parts without departing from the spirit and scope of my invention. I do not limit myself, therefore, to the exact form herein shown and described other than by the appended claims.

I claim:

1. A negative holder comprising a plate, a holder member hinged thereto, said plate and member having aligned openings, the edges of said member around the opening therein being formed downwardly and adapted to pass through the opening in said plate in negative engaging position, and resilient fingers having rounded portions adapted to engage the edges of said member and frictionally hold the same in its closed position on said plate.

2. A negative holder comprising a plate, a holder member hinged thereto, said plate and member having aligned openings, the edges of said member around the opening therein being formed downwardly and adapted to pass through the opening in said plate in negative engaging position, resilient fingers having rounded portions adapted to engage the edges of said member and frictionally hold the same in its closed position on said plate, and guide pins on said plate cooperating with openings in said member for guiding the same in closing.

MORRIS ISRAEL SHWARTZ.
